No. 828,775.

PATENTED AUG. 14, 1906.

H. O. PUTT.
TELEGRAPH TRANSMITTER.
APPLICATION FILED JAN. 16, 1906.

UNITED STATES PATENT OFFICE.

HARLIE OGDEN PUTT, OF MILLBURY, OHIO.

TELEGRAPH-TRANSMITTER.

No. 828,775.

Specification of Letters Patent.

Patented Aug. 14, 1906.

Application filed January 16, 1906. Serial No. 296,271.

To all whom it may concern:

Be it known that I, HARLIE OGDEN PUTT, a citizen of the United States, and a resident of Millbury, in the county of Wood and State of Ohio, have invented a new and Improved Telegraph-Transmitter, of which the following is a full, clear, and exact description.

My invention relates to a machine for transmitting by telegraph; and the principal objects thereof are to provide a device which can be mounted under the frame of an ordinary type-writing machine and operated thereby without in any way altering the machine and which will accurately transmit the characters of the Morse or any other alphabet automatically and rapidly and at the same time do away with many of the complications which have heretofore been thought necessary in order to transmit characters by telegraph by the operation of a keyboard. With this object in view I have provided a series of key-stems located in such position that they will normally rest directly under the keys or key-levers of a type-writing machine constructed in the usual manner and be ready to be moved into operative position when the keys are depressed in writing, so that a type-written copy of the message can be produced simultaneously with transmission thereof by telegraph. The construction is such as to allow a free unrestricted downward movement of each key-stem, the transmission being accomplished automatically when the key-stems are released and allowed to rise.

It will be understood that the construction of the machine is somewhat modified according to whether it is to be applied to a type-writing machine of the Remington type, having one keyboard and a shift-key, or to one of the Smith Premier type, having a double keyboard, or to be used independently of a type-writing machine.

Reference is to be had to the accompanying drawings, forming a part of this specification, in which similar characters of reference indicate corresponding parts in all figures.

Figure 1 represents in vertical sectional view a portion of a machine constructed in accordance with the principle of my invention and applied to a type-writing machine of the Remington type, having a shift-key. Fig. 2 is a side elevation of a portion of one of the key-stems, and Fig. 3 is a sectional view on the line 3-3 of Fig. 1.

I have shown the device as applied to a

type-writer 10, having key-levers 11 and a shift-key lever 12. The machine is provided with a supporting-frame 13, which carries a series of bushings 14, passing through openings 15 in the frame and secured thereto by nuts 16 on one side thereof. Passing through each bushing is a key-stem 17, which is supported by a spring 18 in such position that its head 19 rests directly under one of the key-levers in such a manner that it follows the motions of the key-lever, being forced upward into contact with it when the key-lever is in a raised position by means of the spring 18. Connected through the bottom of the bushing 14 is a spring 20, which engages a sleeve 21, that is capable of a slight rotary or oscillating motion thereon. The tendency of the spring is to keep the sleeve or cam in a certain position, and the bushing is provided with a pair of pins 22, projecting through slots 23 in the sleeve and limiting the motion thereof. The lower end of the sleeve is provided with a pair of inclined surfaces 24 and 25 on each side. It will be noticed that the surface 25 is a straight surface extending toward one side of the key-stem 17 from the center, while the surface 24 is curved. There are two of each of these surfaces in the present instance. Each of the surfaces 24 extends upwardly from the lower end of a surface 25 to a point adjacent to the upper end of the other surface 25. These surfaces constitute cams for operating a cross-bar 26, which is fixed to the key-stem 17 to provide for turning the latter. It will be observed that when the key-stem is forced downwardly by the operation of one of the key-levers of the type-writing machine the cross-bar 26 will be forced from the position shown in Fig. 1 and 2 downwardly along the inclines 25, which give it a slight turn in one direction until it reaches the bottom of this incline and slips over the end of the surface 24. When the key-lever is raised and the spring 18 forces the cross-bar 26 upwardly, the cam-surfaces 24 will force the stem to rotate. The purpose of this rotation will now be described.

Movably mounted on the lower portion of the key-stem is a sleeve 27, which is provided with a pin 28, entering a keyway 29 in the key-stem, so that while the reciprocating motions of the key are not transmitted to the sleeve the rotary motion thereof is. This sleeve is provided with two disks 30 and 31, which are composed in the main of conducting material, but are provided with insulat-

- ing-blocks 32 on their surfaces, separated by projections 33 from the conducting material of the disk. The operation of these disks to transmit electrical impulses is well understood, the relative positions and sizes of the portions 32 and 33 determining the character which is to be transmitted. In the present case each disk is provided with two characters on opposite sides and with two brushes 34. Insulating-strips 35 are located at the ends of the characters, so as to provide for allowing the brushes to rest at the end of the stroke without conducting current. The disk 31 is provided with brushes 36, similar to the brushes 34. The two disks are separated from each other by a washer 37, and above the upper one is a washer 38. These washers may serve as bearing-surfaces for the resilient brushes. Outside the parts so far described 15 is a shell 39, of hard rubber, fiber, or any insulating material, and this is provided for supporting the brushes which have been described. It will be seen that upon each operation of a key one of the key-stems will be depressed and both of the disks connected therewith will be rotated when the key is released. In order to provide for regulating and making uniform the return motion of the key-stem, and consequently the rotation of 20 the disks, I have provided a cylinder 40, in which is mounted a piston 41, provided with one or more restricted perforations 42. This piston is mounted on the lower end of the key-stem, and the cylinder is provided with a 25 perforation 43. It will be seen that this prevents the immediate return of the key-stem, but permits it to return gradually and uniformly, so that the characters can be transmitted in a uniform manner.
- 30 It will be observed that in a type-writer having a double bank of keys and no shift-key it will merely be necessary to provide each key-stem with one of the disks which have been described, and my invention contemplates this simplification of the mechanism illustrated in the drawings. When, however, it is desired to apply the device to a machine having one bank of keys and a shift-key, the two disks are employed, both being 35 connected with the brushes at all times, and I provide means operable by the shift-key for opening the circuit through one of the disks at all times, so that only one of the disks can transmit its character, and the character to be transmitted will depend upon the position of the shift-key, it being understood that the character on one of the disks will represent the character printed by the type-writer when the shift-key is in normal position,
- 40 while that on the other represents the character printed when the shift-key is depressed. For the purpose of making these connections I locate under the shift-key lever a shift-key stem 44. This stem is provided with a spring 45 and a head 46, similar to the springs 18 and
- heads 19, and it is also connected with the frame 13 by a bushing 47, similar to the bushing 14, except that it is insulated from the frame by a collar 48. This bushing carries a shell 49, of insulating material, which is provided with a pair of conducting-rings 50 and 51, separated by an insulating-collar 52. The bottom of the shift-key stem 44 is provided with a spring 53, adapted to bear on the inner surface of the shell and of the conducting-collars 50 and 51. When the shift-key is in normal position, the spring 53 bears on the collar 50 and a current is transmitted from a line-wire 54 to a binding-post 55, through the frame of the machine, thence 50 through the several bushings 14 and key-stems 17 to the disks 30 and 31, and from them, by means of brushes 34 and 36, to a pair of conductors 56 and 57. The conductor 56 is connected with the brushes 34, while the conductor 57 is connected with the brushes 36. The conductor 56 is also connected with the collar 50, and consequently the current is free to flow therefrom through the collar 50 to the spring 53 and thence through the bushing 47 and a conductor 58 to a binding-post 59, which is insulated from the frame of the machine, and to the other main 60. When the shift-key is depressed, however, the spring 53 is brought down into engagement 55 with the collar 51, and therefore connected with the conductor 57 and brushes 36, the path of the current being the same as before. It will be seen, therefore, that the position of the shift-key determines which of the disks 100 shall transmit its character upon the rotation thereof.
- Having thus described my invention, I claim—
1. The combination with a type-writing machine having a bank of keys provided with key-levers, of a telegraph-transmitter having a plurality of key-stems each located directly under one of said key-levers, a transmitting device carried by each key-stem, means for rotating each key-stem when moved longitudinally in one direction, and means for regulating the movement of said key-stem in said direction.
  2. The combination with a type-writing machine having a bank of keys and a shift-key, of a telegraph-transmitter having transmitting mechanism adapted to be operated directly by the keys, and a shifting mechanism adapted to be operated by the shift-key, said shifting mechanism including a key-stem, a spring conductor carried by the key-stem and two conductors insulated from each other and each adapted to be engaged by the spring conductor.
  3. A telegraph-transmitter having a series of key-stems located in such relative positions as to engage the lower edges of the key-levers of the type-writing machine when the keys are in normal position, each of said

stems being provided with a transmitting member, and means for rotating said key-stem and member to transmit a character when the key-stem is moved longitudinally in one direction.

4. A telegraph-transmitter having a series of key-stems, the upper ends thereof being located in the same relative positions as the lower edges of the key-levers of a type-writing machine having a universal keyboard, each key-stem being provided with a transmitting-disk having conducting and insulating portions arranged to form characters, a contact member engaged by said disk, and means for rotating said key-stem and disk to transmit a character when the key-stem is reciprocated.

5. A telegraph-transmitter having a series of key-stems corresponding to the key-levers of a type-writing machine, each key-stem being provided with a conducting-disk having insulating portions thereon, a brush engaging the surface of said disk, and means for rotating said key-stem and disk to transmit a character when the key-stem is raised.

6. A telegraph-transmitter having a series of key-stems corresponding to the key-levers of a type-writing machine, each key-stem being provided with a conducting-disk having insulating portions thereon, a brush engaging the surface of said disk, and means for rotating said key-stem and disk to transmit a character when the key-stem is raised, said means comprising a stationary cam-surface and a bar mounted on the key-stem and engaging said surface.

7. A telegraph-transmitter comprising a key-stem, a spring for normally raising said key-stem, a stationary sleeve mounted adjacent to said key-stem and having an inclined surface and a cam-surface thereon, a telegraph-transmitting disk connected with said key-stem, and a bar mounted on the key-stem and adapted to engage said surfaces on the sleeve.

8. A telegraph-transmitter comprising a reciprocable and rotatable key-stem, a sleeve surrounding said key-stem and having a pair of oppositely-inclined surfaces and a pair of oppositely-located cam-surfaces, each cam-surface extending from the bottom of one of the inclined surfaces to the top of the other, a cross-bar extending in two directions on said key-stem and engaging two sets of surfaces on the sleeve.

9. A telegraph-transmitter comprising a reciprocable and rotatable key-stem, a sleeve surrounding said key-stem and having a pair of oppositely-inclined surfaces and a pair of oppositely-located cam-surfaces, each cam-surface extending from the bottom of one of the inclined surfaces to the top of the other, a cross-bar extending in two directions

from said key-stem and engaging two sets of surfaces on the sleeve, a transmitting-disk 65 and means for transmitting the rotary motion of the key-stem to the transmitting-disk without transmitting the reciprocable motion thereto.

10. In a telegraph-transmitter the combination of a reciprocable and rotatable key-stem having a longitudinal keyway, means for rotating said key-stem when moved longitudinally in one direction, a transmitting-disk, means for supporting said transmitting- 75 disk having a pin projecting into said keyway and means for regulating the motion of said key-stem in one direction.

11. In a telegraph-transmitter the combination of a reciprocable and rotatable key- 80 stem, a transmitting-disk located adjacent thereto, means for transmitting the rotary motion of the key-stem to the disk, a cylinder located adjacent to the key-stem, a piston secured to the key-stem and located in the 85 cylinder, said piston being provided with perforations, and said cylinder with a perforation between its end and the piston.

12. In a telegraph-transmitter the combination of a reciprocable and rotatable key- 90 stem having a longitudinal keyway, means for rotating said key-stem when moved longitudinally in one direction, a transmitting-disk, means for supporting said transmitting- 95 disk having a pin projecting into said keyway, means for regulating the motion of said key-stem in one direction, a second transmitting-disk connected with the first disk and movable therewith, a brush for each disk and means for connecting one of said 100 disks with an electric circuit and disconnecting the other therefrom.

13. A telegraph-transmitter comprising a key-stem having a pair of transmitting-disks and means for simultaneously rotating said 105 disks, a brush for each disk, an electric circuit having one terminal connected with both of said disks, a pair of conducting elements, each electrically connected with one of said brushes, and movable means connected with the other terminal of the circuit for engaging either of said conducting elements.

14. A telegraph-transmitter comprising a shift-key stem having a conducting-spring 115 thereon, an insulating-shell provided with two conducting-collars insulated from each other and both adapted to be engaged by said spring.

In testimony whereof I have signed my 120 name to this specification in the presence of two subscribing witnesses.

HARLIE OGDEN PUTT.
